BUILDING WALL

Robert R. Kellier, 150 Milford St., Manchester, N.H.
Filed Nov. 18, 1959, Ser. No. 853,790
1 Claim. (Cl. 189—34)

This invention relates to building walls and more particularly to wall panels having large continuous surface areas, for use as outer and inner walls of buildings and for partitions. The application is a continuation-in-part of my copending application, now issued as Patent No. 2,931,468.

The existence of thin, high-grade sheet materials, plastics, fibers, minerals and metals, has caused hope that bricks, lumber and concrete would be replaced by more economical building walls which are highly improved in appearance, much lighter and hence easier to erect and which require little or no maintenance throughout a long life. But, in addition to remaining less expensive, conventional materials have been regarded as more reliable in appearance and in resistance to impact loading.

Lightweight panels made from available high-grade thin sheet materials have generally had an unsightly, unevenly dished appearance. Such panels placed side by side have not presented a consistent appearance, but rather uneven shadow effects have occurred, due to the unevenly dished nature of surfaces of the panels. Such panels have also had low impact resistance being damaged in appearance by impinging impact loads and frequently in structure as well. Stiff high-grade sheet materials (e.g., high-density cement-asbestos) have had such low resistance to impact loading as to have been completely unusable for walls in office buildings and others, where long life and good appearance are important factors. Panels without at least one of these defects have not been economically competitive with conventional materials, and have, therefore, found application only where expense has been of little importance.

The principal object of this invention is, therefore, to produce improved building wall panels of high-grade, thin sheet materials.

Another object is to provide wall panels having a consistent, even appearance. Panels following the invention can have glossy, smooth, highly polished outer skin surfaces, undished and completely planar.

Another object is to provide panels having very thin surface skin members with high impact resistance.

A still further object is to provide lightweight wall panels constructed with a minimum of expensive materials, having a large span between stiffener members.

Achievements of the invention include the provision of prefabricated building panels having good insulation and sound absorption features and which provide fire barriers.

The invention comprises an interior, low-density sheet member having a mutual extent with and bonded continuously to the inner surface of a continuous high-grade skin member, but having spaced-apart elongated interruptions, and spaced-apart, elongated rigid stiffener members bonded directly to the skin member at the interruptions. Where the panels comprise structural members, and not mere curtain walls, a second skin is bonded on the other side of the stiffener members.

The low-density thick backing sheet material must have the following characteristics: It must be relatively thick, a thickness of $\frac{3}{8}$ " and upwards to 1", preferably between $\frac{1}{2}$ " and $\frac{3}{4}$ ". It must have a non-friable face directed toward the high-grade skin member, "non-friable" being used in the sense that surface material must not rub off or otherwise separate from the general mass of low-density material. This non-friable surface must conform to the matching surface of the skin member. The low-

2

density sheet must have substantial structural stability and stiffness. Where the sheet is fibrous, affected by moisture to become less stiff, upon the face opposite from the bonded skin there must be a vapor barrier, preferably a very thin impermeable sheet such as polyethylene or aluminum coated paper, laminated thereto.

Skin members according to the invention must be continuous weather and wear resistant sheets of a thickness generally less than $\frac{1}{8}$ ", in many preferred embodiments less than .080" and must be "high-grade": highly compact with hard and non-friable surfaces and having a relatively high internal strength with a tensile yielding point generally above 1000 p.s.i. where thicknesses around $\frac{1}{8}$ " are employed, and proportionately higher specific strengths for thinner members. The high-grade material may be fairly brittle as is high-density cement-asbestos, but not extremely brittle as in glass.

A continuous film of flexible adhesive must bond together the matching surfaces of the interrupted low-density sheet and the skin member throughout their mutual extent.

The rigid, elongated stiffener members fitting the interruptions in the low-density sheet have non-friable conforming surfaces directed towards the inner surface of the continuous skin member. A film of high-grade adhesive material is interposed, directly bonding each stiffener member to the skin. In structural panels a second continuous skin member, also of high-grade material is generally parallel to the first skin member, separated therefrom by the stiffeners and is bonded through matching non-friable surfaces to them. Where both sides of a structural panel are exposed to impact loads and to view, a low-density sheet member is bonded to each of its skin members.

The invention is further amplified in the following detailed description including illustration of a number of preferred embodiments in the drawings wherein:

FIG. 1 is a perspective, exploded view of a typical prefabricated structural wall panel constructed according to the teachings of this invention;

FIG. 2 is a section of the panel of FIG. 1 along line 2—2;

FIG. 3 is a perspective partially cut-away view of another preferred embodiment of a prefabricated structural wall panel;

FIG. 4 is a section of the panel of FIG. 3 taken on lines 4—4;

FIG. 5 is another section of the panel of FIG. 3 along line 5—5 thereof showing in particular the construction of the core;

FIG. 6 is a section similar to that of FIG. 5 of another preferred embodiment of the invention;

FIG. 7 is a section similar to FIG. 4 of another preferred structural panel of the invention for use where both surfaces are exposed to view and to impact loads;

FIG. 8 is a fragmentary perspective of a large prefabricated curtain wall panel in which plastic stiffeners are employed; and

FIG. 9 is a magnified, partially cut-away perspective of an embodiment wherein a moisture barrier is employed.

Thickness of the skins and the films of adhesive and clearances between low-density sheet interruptions and stiffener members are generally exaggerated for the purposes of illustration.

As noted above there exists a number of "high-grade" materials produced in very thin continuous sheets.

Skin walls of many of these high-grade materials yield slightly at varying rates across the surface thereof in response to heating, cooling, wind conditions and other factors, dishing in irregular amounts across the surface, forming a very undesirable dished appearance. In the

case of planar panels this dishing is characterized as a non-planar irregular surface with high points appearing at points of attachment of the skins and irregular depth low points across the surface between. Increase in thickness of the skin decreases the dishing tendency, but such improvement is made only by greatly increasing the cost per unit area of the wall, and the weight thereof. The invention eliminates dishing in a panel surface so that instead of increasing the thickness of the expensive high-grade sheet material, it is possible to utilize much thinner skin members permitting substantial savings.

The invention, in addition, permits great increases in the impact resistance of skins. This "impact resistance" concerns the withstanding of such concentrated loads as may occur when stones or baseballs are thrown against a building wall; when air rifles are discharged thereagainst; and from impacts from kicking or scuffing or moving furniture thereagainst. To be acceptable, walls must withstand such impact loads, not only without structural failure, but without surface changes such as cracking, denting, pitting and crazing.

Following the invention relatively brittle materials, heretofore unsuitable because of cracking and failure under low impact loads (e.g. high-density cement-asbestos), can now be utilized in permanent structures, e.g., as outer walls of office buildings; denting by local stretching beyond the elastic limit as in extremely thin metal sheets is avoided; and crazing as occurs in plastic sheets is eliminated.

All of this is accomplished while providing a structure in which center distances between elongated stiffener members are unusually great, providing a minimization of relatively heavy and expensive stiffener material.

The embodiments of FIGS. 1-7 show structural panels, with dishing eliminated and impact resistance increased in both surfaces for use as inside and outside walls.

Referring to FIGS. 1 and 2 there is a prefabricated structural panel having a length of 10 feet and a width of 4 feet. A strong, compact, hard, non-friable surfaced weathering skin member 12, plastic sheet, having a thickness less than about .030", comprises one surface of the panel. As illustrated this sheet is fiber-glass reinforced polyester plastic, but may obviously be formed of other such plastics, e.g. vinyls, Bakelites (phenolic) and acrylics reinforced where necessary with paper, wire, glass, and the like.

Upon the interior area of this skin is a low-density thick and stiff backing sheet material 14 of fiberboard formed from reclaimed newspapers, with a thickness of about $\frac{1}{2}$ " having a non-friable face towards the skin and having spaced-apart elongated interruptions 16, 18. The low-density sheet covers the entire inner area of the skin except for the interruptions, and is bonded thereto with a continuous film 20 of a flexible bonding agent, e.g., a plastic or rubber base adhesive.

Elongated rigid stiffener members 22, 24 fitting the interruptions are inserted therein. These stiffener members provide non-friable bonding areas conforming with the inner surface of the skin member, and a high-strength bonding material 26 is interposed between the stiffener members and the matching skin area, effecting a high-strength direct bond therebetween. The rigid stiffener members 22, 24 are strong and lightweight. In this embodiment the stiffener members 24 are "box" shaped with I shaped members 22 having spaced-apart longitudinal slides 23 in which end projections 25 of abutting members 22 interlock for sliding engagement following the teachings of my abovementioned copending application, and flanges of members 24 and 22 oppositely directed from skin member 12 are bonded to a second wear resistant skin member 30 generally parallel to the first. This second skin, a high-grade sheet, is of high-density melamine sheet .060" thick and is separated from the first skin by the stiffeners interposed therebetween. To

the interior of this second skin is bonded low-density bagasse board 15 interrupted and bonded as is sheet 14. The structural panel thickness may range up to 8", thickness between $1\frac{1}{2}$ " and 4" being presently most common.

The preferred embodiment of FIGS. 3, 4 and 5 is a prefabricated structural panel having a height of 20 feet and a width of 4 feet. The panel 40 comprises an open stiffener frame 42 comprised of I section core elements 43, 43' and 45 of rigid structural material providing oppositely directed bonding areas bonded directly to outer high-grade skins 44, 46 with high-grade bonding material 48. Skin 44 is a high-grade continuous wear resistant sheet (stainless steel of a thickness of about .020") extending across the entire width and length of the panel; skin 46 is also a high-grade continuous sheet (high-density cement-asbestos of a thickness of about $\frac{1}{8}$ ").

An interrupted, interior low-density thick and stiff backing sheet material 50 (low-density asbestos board) with a thickness of between $\frac{1}{2}$ " and $\frac{3}{4}$ " has a non-friable surface geometrically conforming with the interior surface of skin 44. The interruptions of this low-density sheet 50 receive the stiffener members, but the low-density sheet 50 is not bonded to them. A layer of flexible bonding material 52, continuous and coterminous with the low-density sheet portions is interposed between the matching surface of the low-density sheet 50 and the interior surface of skin 44. To the interior of the skin 46, bonded thereto in a like manner, is an interrupted low-density fiberboard 51 of $\frac{1}{2}$ " thickness, formed from reclaimed newspapers.

The stiffener structure of this embodiment also follows my copending application, as shown in FIG. 5. It will be seen that a longitudinal groove 60 is provided along the abutted side of an abutted element 43. A projection means at the end of the abutting element 45, here oppositely directed ears 49, is twisted into this groove preventing endwise removal of element 45 away from element 43.

In FIG. 6 are flanged stiffener members of another preferred embodiment which, while not offering the rigidity of structure of those of FIG. 5, are suitable in instances where the skin members offer substantial strength. An abutted element 61 is abutted by abutting element 62. A longitudinal seating portion 64 (the inside surface of a flange) is provided along the abutted side of the abutted element 60. A projection means 66 is provided at an end portion of the abutting element for slidably engaging the seating portion, while maintaining the outer flange surfaces of abutted and abutting elements in common planes.

During assembly, with slidable connections as shown in FIGS. 1 through 6, as taught in my copending application, the abutting members may be selectively positioned along the sides of abutted members so to fit within the elongated interruptions in the low-density sheet.

Other advantageous embodiments of my present invention do not employ my novel connection between stiffener members.

Referring to FIG. 7 this prefabricated structural panel has a narrow width and is useful for curved walls. Both of the oppositely directed skin wall surfaces have extremely high impact resistance and resistance to dishing, and the panel is, therefore, useful to define both inner and outer walls of a gymnasium. Parallel opposed stiffener members 70 and 72 have opposed U cross-sections with oppositely directed flange bonding areas lying in parallel spaced-apart planes. High-grade continuous wear resistant skin members 74 and 76, each high-density cement-asbestos with a vitrified outer surface, thickness $\frac{1}{8}$ ", extend across the panel, one in each plane being bonded intimately to the flanges with high-strength adhesives 78. On the inside surface of one skin member is bonded low-density thick and stiff backing sheet member 80, a pressed paper sheet of $\frac{3}{4}$ " thick-

ness, and to the other sheet member 82 is a low-density asbestos board $\frac{3}{4}$ " thick, each of which extends continuously across the area of its skin member with elongated interruptions only at the periphery for the stiffeners 70 and 72. A film of flexible bonding material 73 is interposed between the mutual extent of each skin member and its low-density sheet member.

Referring to FIG. 8 a curtain wall comprised of a network of rigid, rectangular cross-sectioned plastic stiffener members 84 and 86 notched for "egg crate" assembly are bonded to a high-grade weather resistant skin 90 of aluminum of .015" thickness. To the entire inside area of sheet 90, interrupted only at the stiffeners, is bonded low-density thick and stiff backing sheet material 92, pressed paper sheet of a thickness of $\frac{3}{4}$ ".

Referring to FIG. 9 a sheet of low-density sheet material conforming to the requirements of the invention is shown. This sheet has a thickness of $\frac{1}{2}$ ". The under surface A is non-friable and conforms to a skin member E to which it is bonded with a flexible bonding agent D. The thick and stiff low-density sheet has a mutual extent with the skin member except for elongated interruptions F. This sheet of low-density material is formed of compressed fibers and although stiff is subject to becoming flexible when subjected to moisture. Laminated to surface B, facing opposite from non-friable surface A is a vapor barrier layer C comprised of a thin plastic sheet laminated thereto. Vapor barrier material is also applied to the edges of the low-density sheet. Rigid stiffener members G are bonded directly to the skin mem-

Wooden and plastic stiffeners with an ordinary rectangular cross-section may be used to advantage in some instances to provide oppositely directed or single bonding areas.

5 To withstand varying wind loading, construction handling and head loads, it is imperative that the rigid stiffeners have non-friable surfaces so as to withstand differential expansion and contraction and must be compatibly bonded to the high-grade skin sheet, at intervals 10 directly thereto. This high-grade bond must be stronger than the permissible flexible bond existing between the interior low-density sheet and the skin sheet as it must transfer stress and afford support, and stiffness currently achieved only by the use of extremely expensive bonding agents. An example of such an adhesive is synthetic rubber base phenolic material. The comparatively narrow nature of the stiffener bonding areas permits the use of such high-grade bonding agents in competitive structures.

The following is a table of some advantageous combinations of high-grade skins and low-density sheet material, combined, according to the teachings of the invention, with the stiffener members, to comprise panels economically competitive with conventional materials. The thick and stiff low density backing sheet in every instance is upwards of $\frac{3}{8}$ " in thickness, preferably within the range of $\frac{1}{2}$ " to $\frac{3}{4}$ ". The face of this low-density sheet bonded to the skin is non-friable. It has substantial structural stability and stiffness, not highly pliable, and is provided with a vapor barrier where subject to softening water vapors.

EXAMPLES OF COMBINATIONS FOR BUILDING PANELS

High-Grade Skins	Low-Density Sheet	Added Advantages
Stainless Steel 0.040" thick-----	Asbestos Board $\frac{1}{2}$ " thick, weight 15 $\frac{1}{2}$ oz./ft. ²	Fire Barrier.
Fiber Glass reinforced Polyester sheet .030" thick, weight 9 oz./ft. ²	Bagasse (Pressed Sugar Cane Fiber) $\frac{3}{8}$ " thick, weight 12 oz./ft. ²	Extremely Light.
High-density Cement Asbestos $\frac{1}{8}$ " thick, weight 20 oz./ft. ² .	Asbestos Board $\frac{3}{4}$ " thick, weight 23 oz./ft. ²	Fire Barrier, High Insulation Value.
Pressed Exploded Fiberboard 0.125" thick, weight 12 $\frac{1}{2}$ oz./ft. ² .	Fiberboard formed of reclaimed News-paper $\frac{1}{4}$ " thick weight 32 oz./ft. ² .	High Sound Absorbency, Ideal Interior Partition.
Plywood 3-ply laminations, .125 thick over-all.	Asbestos Board $\frac{3}{4}$ " thick, weight 23 oz./ft. ²	High Insulation Value.
Anodized Aluminum 0.015" thick-----	Bagasse (Pressed sugar Cane Fiber) $\frac{1}{2}$ " thick, weight 16 oz./ft. ² .	Very lightweight.
Enameled Steel 0.015" thick over-all-----	Fiberboard formed of reclaimed News-paper $\frac{3}{8}$ " thick, weight 24 oz./ft. ² .	Inexpensive Permanence.
High-density Cement Asbestos $\frac{1}{8}$ " thick, weight 20 oz./ft. ² .	Pressed Paper Sheet $\frac{3}{8}$ " thick, weight 24 oz./ft. ² .	Inexpensive Medium Life.
Aluminum 0.015" thick-----	Slightly expanded polyurethane plastic, $\frac{3}{8}$ " thick, weight 15 oz./ft. ² .	Feather weight.

ber, conforming to the interruptions F of the low-density sheet.

As indicated in the drawings, FIGS. 1-7, some preferred forms of the invention are structural panels, which are self-supporting over large areas and which can withstand wind loadings and head loads without additional support. For these structural panels to resist buckling under such loads it is important that the sandwich be relatively deep, i.e. that the opposite skin sheets be spaced apart as high as 8". The depth provides substantial stiffener material spaced from the neutral axis of the panel. The panel acts as a sturdy column, and is, therefore, not subject to buckling failure.

Other preferred embodiments, e.g., FIG. 8, comprise a single continuous weathering wear resistant skin member as a curtain wall with a number of intermediate stiffeners, as well as the edge-stiffeners, comprising a stiffener structure bonded directly to the skin member at the interruptions of the low-density sheet member. These curtain walls are intended to be supported through the stiffeners upon a building framework.

In many preferred forms, the stiffeners have oppositely directed flanges as in hollow box U and I shaped members providing bonding areas with thin web sections. High-density plastic, aluminum and steel are examples of non-friable surfaced material which may be so utilized.

50 No dishing occurs with the above structures. Each combination has extremely high impact resistance. Of course, other combinations of materials under the limitations set forth also achieve improved building panels. Among these are light-transmitting compact plastic facings, backed with light-transmitting slightly expanded plastic foam sheets in a light-diffusing structural panel.

Although low-density sheet materials are pound-for-pound much less desirable from a structural tension and compression standpoint than the high-grade skin materials, 60 they permit decrease in skin thickness to the point that the total weight of the panels is not greatly increased while dishing is prevented. Thus an unbacked skin panel of a given construction and weight which dishes badly and irregularly can be of about equal weight with a panel according to the invention, of similar construction, which does not dish. The reason for this is that the thickness of the interior sheet material as defined provides a substantial amount of rather stiff material spaced apart from any possible bending axis of the interior low-density sheet, preventing bending thereof and thus supporting a thinner skin from dishing either in or out.

65 The low-density sheet has a much poorer surface facing, more subject to damage under impact loading, such as cracking, scratching and denting, as compared with the high-density skin material. But it greatly improves im-

pact resistance of the high-grade skin sheets furnishing in bonded combination with the skin, characteristics lacking in the thin skins. Thin high-grade skin members (compact, hard, non-friable surfaced, strong, not extremely brittle) standing alone, have a number of impact resistance deficiencies found in differing degrees from material to material. Metals and some plastics in thin sheets are ductile and subject to permanent denting and wrinkling; harder plastics are subject to surface pitting and crazing when impact loads impinge thereupon. High-grade skin members less susceptible to these, are inversely much more brittle and subject to cracking and breakage, one example of this sort of material being the thin, high-density cement-asbestos sheet. All high-grade thin skins will have their impact resistance substantially increased by this invention. The improvement in impact resistance is primarily due to the combined effects of distribution of impact loads throughout substantial skin area and impact absorbency.

(A) *Impact Spreading in Skin*

As described above, the low-density sheet material must not be pliable but rather must have structural stability and stiffness, of course, a function of the thickness of the material as well as its particular internal structure. With this degree of stiffness, upon a concentrated impact blow the force tending to deform the skin is transferred through the impact point on the skin member to a much larger area of the interior low-density sheet. In turn, these dispersed forces upon the interior low-density sheet, tending to depress it, are restrained by the adjacent portions of the bonded skin member at points spaced apart from the point of impact, tending to draw those portions of the skin in the direction of impact. A substantial area of the skin is thus slightly deflected and does the work of resisting a concentrated impact blow with no portion of the skin being subjected to stresses in excess of the elastic limit of the material.

(B) *Impact Absorbency*

Impact resistance, especially for those skins which are relatively brittle, lies also in the absorption characteristics of the backing sheet. Cracking and breaking of brittle skins is due in large part to responsive vibrations in the brittle sheet. With the low-density sheet of the invention, the impact shock is transferred into the low-density sheet and is damped, and cracking and shattering are prevented.

Elasticity of the low-density sheet inherent in its stiffness, is imparted to the high-density sheet, achieving greater impact absorption without yielding.

(C) *Decrease in Prestress*

In many previous structures skin members have been prestressed across stiffener members, in order to attempt to prevent dishing. When an impact load occurred, sufficient deflection of the skin to absorb the blow greatly increased the tension stressed at the point of impact, exceeding the elastic limit and causing damage. With the instant invention, however, prestressing to eliminate dishing is not needed and damage is avoided.

It must be appreciated that not one of these effects alone explains the full advantages of the invention in any one embodiment, but there is a cooperation of effects difficult to analyze.

To achieve the surface bond between the inner skin area and the matching low-density sheet adequate to provide the resistance to impact loading it is imperative that each surface be continuous and non-friable, so that a bond therebetween effects a lasting union between the mass of the low-density sheet and the skin to withstand differential expansion and contraction and to give impact resistance. The bonding material must be flexible so that the portions can flex in response to concentrated impacts.

No numerical weight limits are employed herein in

defining the low-density of the thick and stiff backing sheet member without reference to specific material because a very loose composition formed of a material having high molecular weight would not have a non-friable surface, stiffness or structural stability, but would have a higher weight per unit area than for instance, a satisfactory pressed fiber board of the same thickness. What is generally intended by "low-density sheet which has structural stability and stiffness," is a sheet of material having a strong rigid bridged network, but with substantial air space, and, therefore, being capable of being further compacted to a substantial amount during its manufacture. Of course, to be useful herein, the sheet must have a non-friable surface.

As an example, presently known polyurethane expanded foam having a density upwards of 15 lb./ft.² in sheets of $\frac{3}{4}$ " thickness has a sufficiently strong, rigid bridged network to serve as the low-density sheet, while such foams of lower density are inadequate for the purpose having, for instance, insufficient stability and stiffness for use in the instant invention as well as an inadequate surface.

The specific stiffness of the low-density material (modulus of elasticity and the elastic limit) is not specified with numerical limits in defining the low density of the sheet first, because the over-all stiffness of a sheet is a function of the thickness of the sheet which may be varied within the teachings of the invention over a substantial range as well as the specific stiffness. Secondly, the required amount of over-all stiffness depends upon the particular application. As an example, for a backing for skins of fiber glass reinforced plastics, dishing is the greatest problem to be combatted because the reinforced plastic has a comparatively favorable impact resistance apart from impact crazing, due to the high elasticity of the fiber glass. Thus, although the backing material serves both important functions of increasing impact resistance and decreasing dishing, the nature of the required stiffness of the low-density sheet is that the material be rigid but need not have a very high elastic limit. Contrasted with this are skins of extremely thin sheets of steel, more ductile than fiber glass reinforced plastic, being particularly subject to permanent impact denting and wrinkling by yielding, as well as dishing. These thin sheets of steel require not only a stiff interior backing member, but also one having elasticity over a wide range, providing elastic return and efficient spreading of stress to a wide area of the skin relative to the area of impact. High-density cement-asbestos sheet skin members, in further contrast, is weakest from an impact loading standpoint, and absorption of shock being very important, the low-density sheet must have low compaction, and while stiff, is not required to have as high a degree of stiffness as is necessary in some of the other situations.

The teachings herein serve as a complete guide to the assemblyman who will find many combinations obvious, following the teachings herein, using other analogous materials than the examples herein within the spirit and teachings of the invention.

What is claimed is:

A prefabricated building panel comprising a grid formed of a multiplicity of rigid grid members mechanically connected together, each of said grid members having a web and flanges at each edge thereof extending at an angle to said web, the outer surfaces of each of said flanges being substantially flat and parallel to each other, the grid members extending in two directions and defining a multiplicity of open spaces surrounded by said grid members, said flanges at one edge of said webs defining a first set of bonding surfaces, said bonding surfaces being aligned in a single plane, a first outer sheet member extending in said plane over said grid, said first sheet member having an outer wear-resistant surface and an inner bonding surface, said inner bonding surface

bonded with a layer of adhesive face-to-face to said first set of bonding surfaces, said layer of adhesive lying directly between the cooperating bonding surfaces of said first sheet member and said first set of bonding surfaces, said first sheet member extending continuously over all of said open spaces, a multiplicity of stiff, pre-formed backing sheet members one fitted in each of said open spaces in said grid, each backing sheet member having an area substantially corresponding to the area of said first sheet member lying over said open space, each 10 backing sheet member having a planar bonding surface bonded by a layer of flexible adhesive face-to-face to said first sheet member substantially throughout said area, said backing sheet members each being thicker than said first sheet member and structurally of lesser density than 15 said first sheet member and said grid members, the outer surfaces of said flanges on the other edge of said webs defining a second set of bonding surfaces, said second set of bonding surfaces being aligned in a single plane, a second outer sheet member adhesively secured to said 20

second set of bonding surfaces, said second set of bonding surfaces locating said second sheet member in a spaced apart relationship to said backing sheet members, the smallest dimension of each of said open spaces parallel to said planes being substantially greater than the spacing between said planes.
